corporation of Michigan

Application May 3, 1943, Serial No. 485,536

8 Claims. (Cl. 15—9)

1

This invention relates to vacuum cleaners and has particular reference to a novel and very efficient manner of and means for converting a floor type cleaner into one adapted for so-called "off the floor" cleaning.

Our invention has particular application to that type of floor cleaner having a vertical driving motor, a fan driven thereby, a floor nozzle having a communication with said fan and having a surface cleaning member associated therewith, and a driving connection arranged in said communication and extending between said motor and said surface cleaning member for actuating the latter, and, as illustrated in the embodiment of the invention selected for purposes of illustration, consists of a device normally positioned out of said communication and cooperable with said driving connection for rendering the same inoperative, and a coupling insertable in said communication so as to shut off the flow of air from the floor nozzle to the fan and which coupling is adapted to have suction cleaning tools connected therewith, thereby to connect said tools to the fan, said coupling being cooperable with said device for moving the same into and out of said communication in order to render said driving connection inoperative and operative.

Principal objects of the invention are:

To provide simple and convenient means for efficiently converting floor type cleaners for "off the floor" cleaning;

To provide a converter with built-in means for rendering the driving connection inoperative and operative and which means are extremely simple and efficient and are positioned out of the path of flow of air between the floor nozzle and the fan when the cleaner is used as a floor type cleaner;

To provide a floor type cleaner of the type heretofore referred to with converter provisions which permit the cleaner to be pulled over the floor when converted for "off the floor" cleaning; and

To provide a conversion system for vacuum cleaners which includes a converter that effectively breaks the communication between the floor nozzle and the fan and which seats around the driving connection and cooperates therewith for shutting off the communication between the floor nozzle and the fan.

Other objects and advantages of the invention will be apparent from a consideration of the following specification taken in conjunction with

2

the accompanying drawings, of which there are three sheets and wherein:

Fig. 1 is a vertical sectional view through a part of a floor type vacuum cleaner embodying the invention, the hood and other parts being omitted;

Fig. 2 is a horizontal sectional view through the floor nozzle of the cleaner and illustrating the driving connection in its normal operative position and certain parts of the conversion system;

Fig. 3 is a view similar to Fig. 2 but illustrating the arrangement of the parts when the driving connection has been broken;

Fig. 4 is a vertical sectional view taken in a plane along the line 4—4 of Fig. 2;

Fig. 5 is a plan view of part of the nozzle of the cleaner with the converter coupling secured thereto;

Fig. 6 is a vertical sectional view of the cleaner and coupling and taken in a plane along the line 6—6 of Fig. 1;

Fig. 7 is a fragmentary sectional view taken in a plane along the line 7—7 of Fig. 2;

Fig. 8 is a horizontal sectional view taken in a plane along the line 8—8 of Fig. 6, but with the inner sleeve of the coupling in its other position; and

Fig. 9 is a perspective view of the vacuum cleaner, partially illustrated in the foregoing views, with a hose and dusting tool attached thereto for off the floor cleaning.

A floor cleaner of the type with which our new and improved conversion means are particularly useful is illustrated in Fig. 1 and includes a vertical electric motor 10 forming a driving means for a suction creating means which includes the fan 12 arranged in fan chamber 14, the fan 12 being secured to the motor shaft 16 for rotation therewith. The fan is provided with an inlet formed by fan eye 16 and an outlet 18 to which a dust collecting receptacle is adapted to be connected. The cleaner further includes a rotary surface cleaning member such as an agitator or brush 20 which is rotatably mounted within the floor nozzle 22, the mouth 24 of the nozzle being normally positioned slightly above the surface upon which the cleaner is supported by front and rear wheels 26 and 28. An air flow communication 30 connects the nozzle 22 with the fan through inlet 16 so that upon operation of the fan 12, dirt laden air is drawn through the mouth 24 of the nozzle and conducted to the receptacle which is adapted to be affixed to the fan discharge 18. When the cleaner is operated

40

45

50

55

on a surface covering such as a rug, the suction at the mouth of the nozzle induced by operation of the fan draws such surface covering up against the mouth of the nozzle where it is acted upon by the rotary surface cleaning member 20, in this case a rotary brush having bristles 32 which are adapted to sweep and/or beat the carpet to expedite the cleaning thereof.

The fan 12, as previously indicated, is mounted upon an extension of the shaft of the motor 10 and consists of a series of blades extending radially from a hub 34, said hub forming a continuation of the shaft of the motor 10 and extending through the fan inlet 16 substantially at the center thereof and in spaced relation with the edges defining the fan inlet 16 which usually and as illustrated comprises a circular opening having its center substantially coinciding with the center of the hub 34. The hub 34 projects downwardly into the communication 30, which sometimes is considered a part of the nozzle, and is formed to provide a pulley 36 having an elastic endless belt 38 associated therewith so as to be driven thereby.

The belt 38 has driving engagement with a pulley suitably formed on the rotary brush 20 so that normally during operation of the motor 10 and the fan 12 the brush 20 will be driven. As illustrated in Figs. 1 and 2, the driving connection between the surface cleaning member 20 and the motor, and which driving connection includes the pulley 36 and the belt 38, is arranged in and extends through the communication 30 between the front part of the nozzle 22 and the fan eye 16, although it will be observed that the belt 38 is positioned at one side of the communication and closely adjacent the wall thereof. The normal position of the strands of the belt 38 is indicated in dotted lines in Fig. 6, which is a vertical sectional view taken across the communication 30 with the converter coupling therein.

The vertical sides of the communication 30 may be formed by suitably spaced vertical flanges or walls 40 depending from the body of the cleaner and extending between that part of the nozzle 22 in which the brush 20 is arranged and the fan eye. The space between such walls 40 may be closed by a removable generally horizontally disposed plate 42 having upwardly extending flanges 44 which form a seat for receiving the lower edges of the walls 40. The forward end of the plate 42 may be suitably interlocked with a part of the nozzle wall 22 while the rear end of the plate 42 may have a shoulder 48 engaged by a spring clip 48 carried by the cleaner for removably securing the plate 42 in position to close the bottom of the communication 30 between the nozzle and the fan eye. At one side, as illustrated in Fig. 6, the plate 42 has an upwardly extending portion 50 which is provided with two internal shoulders 52 and 54 which form seats for the strands of the belt 38 when the converter coupling is connected to the cleaner. The side wall 40 is cut away to accommodate the portion 50 which includes a continuation of flange 44 for receiving the lower edge of the cutaway portion of the wall 40.

The plate 42 has pulleys 56 and 58 rotatably secured thereto, the plate 42 being embossed as indicated at 60 in Fig. 4 for accommodating the pulley 58 and embossed as illustrated at 62 in Fig. 6 for accommodating the pulley 56. Rivets 64 secure the pulleys 56 and 58 to the plate 42 for rotation about their axis defined by the rivets 64. The pulleys are interconnected by an endless wire belt 66 which is accommodated in suit-

able channels 68 formed in the plate 42. The pulley 58 has secured to the upper face thereof an upstanding lug or finger 70 which normally is positioned out of the communication 30 and as illustrated in Fig. 2. The pulley 58, incidentally, has its pivot disposed off center relative to the axis of the pulley 36.

The side wall 40 is interrupted to provide a vertical port or slot 72 which communicates with 10 a chamber 74 formed in part by the wall 40 and plate 42 and positioned exteriorly of the communication 30. Except for slot 72, chamber 74 is closed.

When the cleaner is used for floor cleaning purposes, that is, when the belt 38 is drivingly connected with the pulley 36, the finger 70 is positioned in the chamber 74 and obstructs the port or slot 72. In this way the finger 70 is normally positioned out of the communication 30 and hence is not in a position to obstruct the flow of dirt laden air between the nozzle 24 and the fan intake 16. Rotation of the pulley 58 one hundred eighty degrees in a counterclockwise direction will shift the lug or finger 70 from the position illustrated in Fig. 2 to that illustrated in Fig. 3. During movement from the position illustrated in Fig. 2 to that illustrated in Fig. 3, the finger 70 will pass below the upper strand of the belt 38 and engage the lower strand thereof in front of the pulley 36 and lift the belt 38 free of the pulley 36, as illustrated in Fig. 3, thereby breaking the driving connection between the motor 10 and the surface cleaning member 20.

Movement of the pulley 58 one hundred eighty degrees in a clockwise direction from that illustrated in Fig. 3 will restore the member 70 to the position illustrated in Fig. 2 and reengage the belt 38 with the pulley 36, thereby reestablishing the driving connection between the motor 10 and the surface cleaning member 20.

When the lug or finger 70, which comprises a belt lifter, is positioned as illustrated in Fig. 3, the port 72 will be closed by a gate 76 which is formed on the end of a spring 78 seated within 45 the chamber 74.

On its under face the pulley 58 is provided with a groove 71 which is formed as a semi-circle around the pivot of the pulley 58. A lug 79 projecting upwardly from the plate 42 extends into 50 the groove 71 for limiting the extent of oscillation. The pulley 58 is shifted from one of its positions to the other by oscillation of the pulley 36, which in turn is shifted by the coupling member indicated generally at 80 and as hereinafter 55 set forth.

Pulley 56 is provided with an upstanding key 82. The coupling member 80 consists of a pair of sleeves 84 and 86, the sleeve 86 being rotatably fitted within the sleeve 84. The coupling member 86 is adapted to be inserted through a port 88 formed in the upper wall 90 of the nozzle and the inserted ends of the sleeves 84 and 86 are shaped to seat on the pulley 56, the inner sleeve 86 being provided with a slot 92 which receives the key 82.

The slot 92 is formed by cutting away a portion of the bottom edge of the sleeve 86 corresponding in shape to the cross section of the key 82. The outer sleeve 84 has a shape corresponding to the shape of the port 88 and has a snug fit therein, and the sleeve 84 may have an annular shoulder 94 which seats on the wall 90 around the port 88. The inner sleeve 86 projects above the outer sleeve 84 and has secured thereto a collar 88 by means of which the inner sleeve may be 75 rotated from one of its positions to the other.

An elbow 98 is swiveled between the end of the sleeve 86 and an internal shoulder formed on the collar 96 and the elbow 98 may have connected thereto or be formed for connection with a flexible air conducting hose 100 to the other end of which suction cleaning tools are adapted to be connected. The coupling member 80, which includes the sleeves 84 and 86 together with the elbow 98, forms a hollow air conducting member.

The outer sleeve is provided with laterally extending vertical wings or guides 102 and 104 which are adapted to pass through slots communicating with the port 88 and when arranged as illustrated in Fig. 6 are adapted to cooperate with the sleeves 84 and 86 and the walls of the passage 30 for shutting off the communication between the fan inlet 16 and the mouth 22 of the floor nozzle. The wing 104 is formed with shoulders 106 and 108 which are adapted to seat against the strands of the belt 38 and force the same against the seats 52 and 54 formed by the portion 50 of the bottom plate 42, thereby effectively sealing the space on one side of the converter coupling 80 from the space on the other side thereof. The wing 102 closes the space between the sleeve 84 and the right side of the passage 30, looking at Fig. 6.

After the coupling member is inserted through the port 88 and positioned in the cleaner as illustrated in Fig. 1, manipulation of the collar 96 by turning the same through 180° of rotation will, through the pulley 58, belt 66, and pulley 58, shift the belt shifter from the position illustrated in Fig. 2 to that illustrated in Fig. 3, or otherwise stated, will lift the belt 38 from the pulley 36. Reversal of movement of the collar 96 will shift the belt shifter 70 back to the position illustrated in Fig. 2 and the sleeve 86 and pulley 58 back to the position illustrated in Fig. 1.

A part of the sleeve 84 facing the pulley 36 is cut away as indicated at 110 in order to establish communication between that part of the passage 30 between the coupling 80 and the fan eye 16 and the interior of the coupling 80. The cut-away portion 110 is closed by the sleeve 86 when the coupling is initially inserted in the machine. The sleeve 86 is provided with a similar port or cutaway portion 112 which, when the sleeve 86 is shifted 180° from that illustrated in Fig. 1, becomes aligned with the port 110 thereby to establish communication between the passage 30 and the interior of the coupling 80, as shown in Fig. 8.

The sleeve 86, as previously stated, is shifted by turning the collar 96. As the sleeve 86 cooperates with the key 82 to rotate the pulley 58, the belt 38 is lifted from the pulley 36 at the same time that communication is established between the interior of the coupling 80 and the passage 30, and similarly as the driving connection is re-established the communication between the interior of the coupling 80 and the passage 30 is shut off. As previously indicated, the positioning of the coupling 80 within the cleaner shuts off the communication between the mouth 24 of the nozzle and the fan eye 16. Therefore, when the converter is employed to connect suction cleaning tools to the fan, the communication of the fan with the floor nozzle is shut off and the driving connection between the motor and the surface cleaning member 20 is broken. As the converter coupling 80 projects forwardly and upwardly from the center of the cleaner adjacent the front thereof, the cleaner at such time may readily be pulled about on the floor by the flexible

hose which is connected to the converter coupling 80.

A ball detent 120 is operatively positioned between sleeves 84 and 86 for locating the position of one relative to the other. When the sleeve 86 is rotated, the detent 120 moves out into a recess in the sleeve 84 and projects from the surface of the sleeve 84. This ball detent 120 thus cooperates with the under surface of the wall 90 adjacent the port 88 for locking the converter in position in the cleaner. Thus, in order to insert or remove the converter coupling 80 from the cleaner, the sleeves must be positioned relative to each other as illustrated in Fig. 1, otherwise the ball detent 120 will engage the edge of the port 88 and prevent the seating of the converter coupling or the removal of the converter coupling. The ball detent 120 will by gravity assume the position illustrated in Fig. 1, but will be forced out of such position by turning movement of the sleeve 86.

As shown in Figs. 2 and 3, the side walls of the passage or communication 30 may be provided with inwardly extending ribs 120 which function as guides for the wings or flanges 102, 104 and which cooperate therewith to seal the part of the communication 30 upstream of the coupling from that part on the downstream side thereof.

As shown in Fig. 9, the cleaner is provided with a handle by means of which the machine may be maneuvered over a surface or surface covering which is to be cleaned by the machine. This handle is adapted to be parked in a vertical position when the machine is pulled about by means of the flexible hose 100 which is connected to the converter coupling and which in turn is connected to the front of the cleaner. When the converter coupling 80 is separated from the cleaner the port 88 and the slots communicating therewith are adapted to be closed by a suitable cover so that at such time the nozzle mouth 24 is operatively connected with the fan inlet 16 and the rotary brush 20 in the nozzle 22 is driven by the motor during the operation of the fan.

The terms "agitator," "surface cleaning member," or "rotary brush" as used herein are employed generically to designate elements such as brushes, beaters, polishers, or other devices which may be operatively associated with the mouth of a nozzle of a vacuum cleaner and used either with or without air flow through the nozzle, and which are normally adapted to be actuated during operation of the fan.

While the invention has been described with some detail, it is to be understood that the description is for the purpose of illustration only and is not definitive of the limits of the inventive idea. The right is reserved to make such changes in the details of construction and arrangement of parts as will fall within the purview of the attached claims.

We claim:

1. A vacuum cleaner comprising an electric motor having a vertical shaft, a fan arranged below said motor and connected to said shaft to be driven thereby, said fan being provided with an air inlet on the under side thereof, a nozzle having a downwardly presented mouth and an agitator operatively associated therewith, a belt forming a driving connection between said shaft and said agitator for driving the latter during operation of the fan, a communication forming an air passageway between said nozzle and said fan inlet for inducing a flow of air into said nozzle during operation of said fan, said belt

extending through said passageway, said communication being provided with an upwardly facing air inlet port at the front of said cleaner and which port is normally closed, a converter coupling comprising a hollow unobstructed air conducting member adapted to be removably connected with said port when the same is open, said air conducting member when connected to said port having the end thereof arranged to project into said passageway and seat on the wall thereof opposite said port, said end having provision for accommodating the strands of said belt and conforming to the cross section of said passageway and cooperating with the walls thereof to obstruct said passageway so as to prevent the flow of air from said nozzle to said fan inlet during operation of said fan, said air conducting member when connected to said port being adapted to communicate with said fan inlet through said passageway, and means assembled to said cleaner independently of said converter coupling and cooperable with said belt to disengage the same from said shaft for rendering the driving connection inoperative, said converter having a shiftable part cooperable with said means for operating the same to disengage and engage said belt when said converter is connected to said port.

2. A vacuum cleaner comprising an electric motor having a vertical shaft, a fan arranged below said motor and connected to said shaft to be driven thereby, said fan being provided with an air inlet on the under side thereof and through which said shaft extends, a nozzle having a downwardly presented mouth and an agitator operatively associated therewith, a communication forming an air passageway between said nozzle and said fan inlet for inducing a flow of air into said nozzle during operation of said fan, a belt arranged in driving relationship with said shaft and agitator for actuating the latter during operation of said fan and extending through said passageway, said communication being provided with an upwardly facing air inlet port which is arranged at the front of the cleaner and which is normally closed, a part of said passageway adjacent said port being formed and arranged relative to the strands of said belt so that said strands are positioned in close proximity to a wall of said passageway, a converter coupling comprising a hollow unobstructed air conducting member adapted to be removably connected with said port when the same is open, said air conducting member when connected to said port having the end thereof arranged to project into said passageway and seat therein, said end and said part of said passageway being formed to fit together with the strands of said belt therebetween, said end conforming to the cross section of said passageway and cooperating with the walls thereof to obstruct said passageway so as to prevent the flow of air from said nozzle to said fan inlet during operation of said fan, said air conducting member when connected to said port being adapted to communicate with said fan inlet through said passageway, and a belt lifter assembled to said cleaner independently of said converter coupling and engageable with said belt for disengaging the same from said shaft, said converter having a shiftable part cooperable with said belt lifter for operating the same to disengage and engage said belt when said converter is connected to said port.

3. A floor type vacuum cleaner comprising an electric motor having a shaft, a fan connected to

said shaft to be driven thereby, said fan being provided with an air inlet, a nozzle having a downwardly presented mouth and an agitator operatively associated therewith, a communication forming an air passageway between said nozzle and said fan inlet for inducing a flow of air into said nozzle during operation of said fan, a driving connection between said shaft and said agitator for driving the latter during operation of said fan, said communication being provided with an air inlet port which is positioned out of alignment with said fan air inlet and which port is normally closed, a removable converter coupling comprising a hollow unobstructed air conducting member adapted to be separably connected with said port when the same is open and when so connected to be positioned between said nozzle and said shaft, said coupling when connected to said port obstructing said passageway so as to prevent the flow of air from said nozzle to said fan inlet and having an opening which affords communication with said fan inlet through said passageway, means assembled to the cleaner independently of said converter coupling and cooperable with said driving connection for breaking and remaking the same while said coupling is connected to said port, and an operator for said means mounted on said cleaner adjacent said port and positioned to be engaged by a shiftable part of said coupling when the same is connected to said port and arranged to be actuated by shifting movement of said part for breaking and remaking said driving connection.

4. A floor type vacuum cleaner comprising an electric motor having a shaft, a fan connected to said shaft to be driven thereby, said fan being provided with an air inlet, a nozzle having a downwardly presented mouth and an agitator operatively associated therewith, a communication forming an air passageway between said nozzle and said fan inlet for inducing a flow of air into said nozzle during operation of said fan, a readily removable plate forming the bottom wall of said passageway, a belt arranged in driving relationship with said shaft and agitator for actuating the latter during operation of said fan and extending through said passageway, said communication being provided with an air inlet port which is positioned between said nozzle and said inlet and out of alignment with said fan air inlet and which port is normally closed, a removable converter coupling comprising a hollow unobstructed air conducting member adapted to be separably connected with said port when the same is open and when so connected positioned between said nozzle and said shaft, said coupling when connected to said port having the end thereof arranged to project into said passageway and seat on the wall thereof opposite said port, said end having provision for accommodating the strands of said belt and conforming to the cross section of said passageway and cooperating with the walls thereof to obstruct said passageway so as to prevent the flow of air from said nozzle to said fan inlet, said air conducting member having an opening which affords communication with said fan inlet through said passageway, and a belt lifter mechanism mounted on said removable plate engageable with said belt for disengaging and engaging the same from said shaft when said coupling is connected to said port, said belt lifter mechanism including an operator positioned to be engaged by a shiftable part of said coupling and arranged to be actuated by shift-

ing movement of said part for breaking and re-making said driving connection.

5. A floor type vacuum cleaner comprising an electric motor having a shaft, a fan connected to said shaft to be driven thereby, said fan being provided with an air inlet, a nozzle having a downwardly presented mouth and an agitator operatively associated therewith, a belt arranged in driving relationship with said shaft and agitator for actuating the latter during operation of said fan, a communication forming an air passageway between said nozzle and said fan inlet for inducing a flow of air into said nozzle during operation of said fan, said belt extending through said communication, said communication being provided with a converter air inlet port which is positioned out of alignment with said fan air inlet and between said nozzle and said inlet and which port is normally closed, a converter coupling comprising a hollow unobstructed air conducting member adapted to be removably connected with said port when the same is open and when so connected positioned between said nozzle and said shaft, said coupling when connected to said port having the end thereof arranged to project into said passageway and seat on the wall thereof opposite said port, said end having provision for accommodating the strands of said belt and conforming to the cross section of said passageway and cooperating with the walls thereof to obstruct said passageway so as to prevent the flow of air from said nozzle to said fan inlet, said air conducting member having a lateral opening which affords communication with said fan inlet through said passageway, and a belt lifter assembled to said cleaner independently of said converter coupling and normally positioned exteriorly of said passageway and mounted for movement into said passageway and into engagement with said belt for lifting the same out of driving relationship with said shaft, said belt lifter having an operator positioned to be engaged by a shiftable part of said coupling and arranged to be actuated by shifting movement of said part for breaking and remaking said driving connection.

6. A floor type vacuum cleaner comprising an electric motor having a shaft, a fan connected to said shaft to be driven thereby, said fan being provided with an air inlet, a nozzle having a downwardly presented mouth and an agitator operatively associated therewith, a belt in driving relationship with said shaft and agitator for driving the latter during operation of said fan, a communication forming an air passageway between said nozzle and said fan inlet for inducing a flow of air into said nozzle during operation of said fan, said belt being arranged in said passageway, said communication being provided with an air inlet port which is positioned out of alignment with said inlet and between said nozzle and said inlet and which port is normally closed, a converter coupling comprising a hollow unobstructed air conducting member adapted to be removably connected with said port when the same is open and when so connected positioned between said nozzle and said shaft, said coupling when connected to said port having the end thereof arranged to project into said passageway and seat on the wall thereof opposite said port, said end having provision for accommodating the strands of said belt and conforming to the cross section of said passageway and cooperating with the walls thereof to obstruct said passageway so as to prevent the flow of air from said nozzle to said fan

inlet, said coupling having a part thereof formed to accommodate and seal around said belt, said air conducting member having an opening which affords communication with said fan inlet through said passageway, and a belt lifter assembled to said cleaner independently of said converter and normally positioned exteriorly of said passageway and engageable with said belt for disengaging and engaging the same from said shaft, said belt lifter being constructed and arranged to be actuated by said converter, and a chamber communicating with said passageway for housing said belt lifter when said belt is engaged with said shaft.

7. A floor type vacuum cleaner comprising an electric motor having a vertical shaft, a fan arranged below said motor and connected to said shaft to be driven thereby, said fan being provided with an air inlet on the under side thereof, a nozzle having a downwardly presented mouth and an agitator operatively associated therewith, a driving connection comprising a belt in driving relationship with said shaft and agitator for driving the latter during operation of said fan, a communication forming an air passageway between said nozzle and said fan inlet for inducing a flow of air into said nozzle during operation of said fan, said belt being arranged in said passageway, said communication being provided with an upwardly facing converter port which is positioned between said nozzle and said inlet and which port is normally closed, a converter coupling comprising a hollow unobstructed air conducting member adapted to be removably connected with said port when the same is open and when so connected positioned between said nozzle and said shaft, said coupling when connected to said port having the end thereof arranged to project into said passageway and seat on the wall thereof opposite said port, said end having provision for accommodating the strands of said belt and conforming to the cross section of said passageway and cooperating with the walls thereof to obstruct said passageway so as to prevent the flow of air from said nozzle to said fan inlet, said coupling having a part thereof formed to accommodate and seal around said belt, said air conducting member having an opening which affords communication with said fan inlet through said passageway, and a belt lifter assembled to said cleaner independently of said converter coupling and normally positioned exteriorly of said passageway and engageable with said belt for disengaging and engaging the same from said shaft, said cleaner having an operator for said belt lifter constructed and arranged to be engaged and operated by a shiftable part of said coupling when the same is connected to said port for breaking and remaking said driving connection upon shifting movement of said part.

8. A floor type vacuum cleaner comprising an electric motor having a vertical shaft, a fan arranged below said motor and connected to said shaft to be driven thereby, said fan being provided with an air inlet on the under side thereof, a nozzle having a downwardly presented mouth and an agitator operatively associated therewith, a communication forming an air passageway between said nozzle and said fan inlet, a driving connection comprising a belt in driving relationship with said shaft and agitator for driving the latter during operation of said fan, a removable plate forming the bottom wall of said communication, said belt being arranged in said passageway

11

way at one side thereof, said communication being provided with an upwardly facing converter port which is positioned at one side of said belt and which port is normally closed, a converter coupling comprising a hollow unobstructed air conducting member adapted to be removably connected with said port when the same is open and when so connected positioned at one side of said belt, said coupling when connected to said port having the end thereof arranged to project into said passageway and seat on the wall thereof opposite said port, said end having provision for accommodating the strands of said belt and conforming to the cross section of said passageway and cooperating with the walls thereof to obstruct said passageway so as to prevent the flow of air from said nozzle to said fan inlet, said coupling having a part thereof formed to accommodate and seal around said belt, said air conducting member having an opening which affords communication with said fan inlet through said passageway, a belt lifter assembled to said removable bottom plate and normally positioned exteriorly of said communication and operable for disengaging and engaging said belt, from said shaft, and an operator for said belt lifter positioned below said port and constructed and arranged to be engaged and operated by a shift-

5

12

able part of said coupling when the same is connected to said port for breaking and remaking said driving connection upon shifting movement of said part.
